US00D649550S

(12) **United States Design Patent**
Segui Tomas et al.

(10) **Patent No.:** **US D649,550 S**
(45) **Date of Patent:** **** Nov. 29, 2011**

(54) **AUGMENTED REALITY DEVICE**

(75) Inventors: **Ignacio Segui Tomas**, Alcoi (ES);
Francisco Ibañez Garcia, Villena (ES);
Tomas Munkvold, Trondheim (NO)

(73) Assignees: **Asociacion de Investigacion de la Industria del Juguete, Conexas y Afines**, Ibi (Alicante) (ES); **Brainstorm Multimedia, SL**, Valencia (ES)

(**) Term: **14 Years**

(21) Appl. No.: **29/338,626**

(22) Filed: **Jun. 16, 2009**

(51) LOC (9) Cl. **14-02**

(52) U.S. Cl. **D14/411**

(58) **Field of Classification Search** D14/388,
